UNITED STATES PATENT OFFICE.

CHARLES P. EISENHAUER, OF DAYTON, OHIO, ASSIGNOR TO THE DURO COMPANY,
OF DAYTON, OHIO, A CORPORATION OF OHIO.

PUMP.

Application filed February 28, 1927. Serial No. 171,517.

My invention relates to valves for pumps. It is the object of my invention to provide a valve which will have the maximum of area for the escape of liquid, and will, at the same time, be noiseless, so that a rapid reciprocation of pumping mechanism will not set up objectionable valve noise.

Referring to the drawings:

Figure 1 is a section through the cylinder inlet housing, piston and valve mechanism, as well as the inlet housing with the parts in position for ejection of the liquid;

Figure 2 is a view of the parts in balanced condition;

Figure 3 is a view of the parts in discharge condition.

Referring to the drawings in detail, 1 is a housing containing an inlet chamber 2 into which liquid is introduced through the inlet opening 3.

The liquid makes its exit through the ports 4 into the cylinder sleeve or casing 5 carried within the main casing 1. The piston rod 6 is provided having mounted thereon a piston 7 and a washer 8. This piston has connected to it and its rod by the screw 9 a spider having openings 11 through which the fluid in the cylinder is adapted to flow into the interior of a cylinder 12 formed on the end of the spider 10. This cylinder constitutes a second piston which also carries a washer 8 engaging with the side walls of the cylinder 5. Mounted on the second piston 12 is a ring 13 which carries one end of a helical spring 14, the coils of which are normally in engagement with one another. The end of the spring is sealed by a plug 15 supported by the spring so that when the spring is in position of rest the end of the cylinder 12 is sealed by the spring 14 and its cap 15 forming a fluid tight chamber.

This chamber formed of the spring 14 and its end 15 is adapted to telescope within a similar but larger chamber formed by a helical spring designated 16 having an end cap 17. This spring is supported by a ring 18 carried within a larger plate 19 between the casing 1 and the exit casing 20. This spring 16 also normally is so arranged that its coils engage one another forming a closed cylinder.

The main cylinder and intake casing and the exit casing respectively numbered 1 and 20 are held together by one or more bolts, such as 21, such bolts passing through the

ring 19, the junctures between the ring and the two casings being sealed by the washers 22.

Method of operation.—When the piston and piston rod moves to the right hand, 60 water is drawn in through the openings 11 to the interior of the cylinder 12 and the interior of the spring 14. The pressure of compression of this water serves to move this spring laterally, separating its coils and permitting the water to escape between the coils. The vacuum created in between the valves causes the spring 14 to open, allowing the water to enter the piston chamber.

This permits of a large number of separate 70 annular openings being provided and therefore a large area for the quick exit of the water.

Upon the return towards the left of the piston and piston rod, these coils of the spring 75 again close forming a solid closed cylindrical surface for the compression of the water which is now within the outer spring 16 so that it in turn is expanded and the water makes its exit between the coils of the spring 80 16 into the exit chamber in the casing 20, thence out the exit opening 23.

This arrangement has a dual advantage.

In the first place, the operation of the valve formed by the coils of the spring permits of a very rapid and noiseless valve mechanism. In the second place, the area is very large over the exit of the water because, instead of having a single opening between a valve member and its exit, there are many similar openings for this purpose, as there are coils of the spring which may be separated. The timing of the valve mechanism is perfect because it depends upon the alternate compression and ejection of the water. When the piston is moved towards the left hand it is sucking in water and when it moves towards the right hand the water is compressed on the interior of the first expanding it and so on.

It will be understood that I desire to comprehend within my invention such modifications as may be necessary to adapt it to varying conditions and uses.

Having thus fully described my invention, 105 what I claim as new and desire to secure by Letters Patent, is:—

1. A new article of manufacture for use as a valve consisting of a helical spring having one end open for the introduction of 110

fluid on the interior thereof and the other end closed, whereby upon a predetermined pressure being achieved on the fluid on the interior of the spring its coils will be spread 5 and the exit of the fluid will take place.

2. In combination, a cylinder, a piston and piston rod and a valve means carried by said piston adapted to receive water from the cylinder consisting of a helical spring 10 having its coils normally closed, and a sealing member for the end of said spring, the other end of the spring being open for receiving the fluid from the cylinder.

3. In combination, a cylinder, a piston 15 and piston rod and a valve means carried by said piston adapted to receive water from the cylinder consisting of a helical spring having its coils normally closed, and a sealing member for the end of said spring, the 20 other end of the spring being open for receiving the fluid from the cylinder, and a second larger spring similarly arranged adapted to receive liquid from the first mentioned spring and whereby the movement of 25 the piston in one direction will result in the opening of the first mentioned spring for the passage of fluid therethrough and the movement of the piston in the other direction will result in the opening of the second spring 30 for the exit of fluid therefrom.

4. In combination, a cylinder, a piston and piston rod, said cylinder having an entrance opening in front of said piston, a second piston spaced from the first piston, 35 said second piston being hollow and having openings for the introduction of fluid from the cylinder into the interior thereof, and yielding means closing the end of said second piston adapted to expand and permit the 40 exit of fluid under compression of the fluid within said yielding means.

5. In combination, a cylinder, a piston and piston rod, said cylinder having an entrance opening in front of said piston, a second piston spaced from the first piston, said second piston being hollow and having openings for 45 the introduction of fluid from the cylinder into the interior thereof, and yielding means closing the end of said second piston adapted to expand and permit the exit of fluid 50 under compression of the fluid within said yielding means, and a second yielding means

adapted to telescope to receive the first yielding means having one end thereof sealed whereby the fluid compressed therein by the 55 first yielding means may escape through the second yielding means.

6. In combination, a cylinder, a piston and a pair of telescopically arranged helical springs having closed ends at one end and 60 open ends at the other for receiving fluid, one of said springs being stationary and the other being movably connected to said piston.

7. In combination, a cylinder casing having an inlet port arranged between a pair of spaced pistons therein, a pair of spaced pistons, a piston rod, one of said pistons being hollow and adapted to receive liquid from the cylinder into the interior thereof, a helical spring having normally closed coils mounted in the end of said hollow piston, means to close the end of said spring, a second helical spring having a closed end of 70 normally closed coils of larger diameter than the first helical spring, stationarily mounted at the end of said cylinder adapted to telescopically receive the first mentioned spring, and an exit chamber surrounding said second spring. 80

8. In combination, a cylinder having a stationary wall with an inlet port and a yielding normally closed expansible wall, a pair of spaced pistons having a portion formed into a cylinder adapted to communicate with the interior of the main cylinder, said piston having a wall of yielding expansible material adapted to permit the escape of liquid therein under pressure. 85

9. In combination, a cylinder, a hollow 90 piston adapted to receive liquid from the cylinder, said piston having an expansible wall for the exit of liquid therethrough when the liquid is compressed within said wall, a piston, and an expansible wall of 95 expansible yielding material forming a part of said cylinder adapted to permit the escape of liquid compressed between said yielding expansible wall and said hollow piston. 100

In testimony whereof, I affix my signature.

CHARLES P. EISENHAUER.
